UNITED STATES PATENT OFFICE.

FREDERICK F. MILLER, OF NAPANEE, ONTARIO, CANADA.

INTERNAL-COMBUSTION ENGINE.

No. 884,402.

Specification of Letters Patent. Patented April 14, 1908.

Application filed April 3, 1907. Serial No. 366,216.

To all whom it may concern:

Be it known that I, FREDERICK FRASER MILLER, subject of the King and Queen of Great Britain, residing in Napanee, Province of Ontario, in the Dominion of Canada, have invented certain new and useful Improvements in Internal-Combustion Engines, of which the following is a full, clear, and exact description.

10 My invention relates to improvements in what is commonly known as a two-cycle, internal combustion engine, and has for its object to provide an engine which is flexible and economical by improving the scavenging qualities, by obtaining a more perfect carburation of air especially when working under a throttle mixture, to prevent the loss of unburned gaseous mixture through the exhaust, to assist in cooling the cylinder and prevent 20 initial firing. I attain these objects by the combination with the engine of a separate air pump and two variable storage chambers for air.

25 My invention includes the various features which will be evident from the following description and are particularly set forth in the claims.

Referring to the accompanying one sheet of drawings in which similar characters of 30 reference indicate like parts throughout the several views, Figure I is a sectional elevation of a single cylinder engine and related parts. Fig. II is a sectional elevation of a two-cylinder engine illustrating a modification in arrangement of related parts.

35 In the drawing I illustrate the air pump's cylinder and piston as a prolongation of their respective engine cylinders and pistons. It is not necessary to put the air pump in this position and a separate air pump may be used if desired. I make no claim to this position, or this form of annular air pump.

The frame of the engine may be of any suitable construction and is conventionally shown in the drawings and indicated by the reference-numeral 1. This frame may include a crank-case and suitable connections between the crank-case and the cylinder portion of the frame. The cylinder 2 may be provided with the usual water-jacket 3. If found necessary, a circulation of water may be maintained within the water-jacket in order to keep the sides of the cylinder properly cooled and to preserve lubrication. The crank end of the engine cylinder 2 is prolonged forming cylinder 4 having a longer

diameter than the engine cylinder, the purpose of which will be explained fully later on.

5 is a shaft mounted in bearings 6 provided with cranks 7.

Referring more particularly to Fig. I of the drawings hereto annexed, I have shown a single cylinder, two-cycle vertical engine with inlet 8 and exhaust 9, both of which are opened and closed mechanically by the movement of the piston 11.

For a full understanding of the construction of the apparatus, it is essential to describe in detail only the parts which coöperate with one cylinder and to point out thereafter 70 any modification of the connections between the parts when the cylinders are multiplied.

10 is a connecting rod between the cranks 7 and the engine piston 11. The crank end of piston 11 is extended and forms piston 12 75 which movably fits the cylinder 4. The pistons 11 and 12 are fitted with regulation piston packing 13. These being well known need not be described. On the inlet side of piston 11 is provided a projection 33, the 80 purpose of which is to direct the circulation in the cylinder 2.

14 is an air inlet which is opened and closed mechanically by the reciprocating piston 12.

85 15 is any well known form of ignition, preferably the spark or firing plug type.

16 is a cylinder provided with a piston 17 which divides the cylinder 16 into two chambers 18 and 19, the volumes of which are 90 variable inversely by shifting the piston 17 by means of its rod and connections. Chamber 18 is connected direct to the engine cylinder 2 by piping through the main inlet 8. The air pump cylinder 4 is connected direct 95 to chamber 18 by piping 20 which is provided with a check valve 21. Chambers 18 and 19 are connected by a line of piping 22 in which is connected a carbureter chamber 23. This carbureter chamber is illustrated on the drawings as an outside elevation, purposely, because in this application no claim is made whatever upon the style of carbureter used. A subsequent application will disclose the details of a carbureter preferred for this engine. This carbureter chamber is connected 100 to the carbureting fluid tank, or pump if that is used in place of carbureter, by the pipe 24. The air in chamber 19 may be carbureted either by an automatic carbureter or a 110 variable feed pump supplying the exact quantity of carbureting fluid or gas to

properly carburet the air in the chamber. Cylinder 4 may be of such a diameter that the volume of air pumped by the annular air pump is somewhat larger than the volume of the engine cylinder 2.

Referring to Fig. II, the arrangement of parts and the piping, is a slight modification of that fully described above and illustrated in Fig. I. Chamber 18 is connected to power cylinder of second engine; this obviates the necessity of the check valve 21 in line of piping 20, as will be readily understood. Otherwise, the various features are the same. The usual oil-ducts may be provided at any convenient point throughout the engine.

The operation of the engine is as follows: Supposing the pistons 11 and 12 are at their lowest point of the stroke, as illustrated in the right-hand engine in Fig. II. On the upward stroke the mixture in cylinder 2 is compressed, and the air in cylinder 4 is compressed into chambers 18 and 19, the air is carbureted in 23 either going to or coming from chamber 19. The ignition device fires the charge in cylinder 2, at the proper time, and the piston 11 is forced down and opens the exhaust 9 and inlet 8. The burned gases exhaust, being forced out by the inrush of fresh air from chamber 18 through inlet 8. This pure air is then forced out in turn by the inrush of the carbureted air from chamber 19. The exhaust and inlet valves are mechanically closed and the operation is repeated.

To throttle the engine it would only be necessary to shift piston 17 so as to increase volume of chamber 18 and decrease volume of chamber 19 and as the carbureted air is the last to enter engine cylinder 2 it would not drive out all the air and remaining burned gases in engine cylinder 2. The mixture, therefore, would remain pocketed about the inlet side of cylinder 2 and would be compressed about and fired at 15, and as it would be a perfectly carbureted mixture, it would have more explosive power than a very weak charge filling the whole cylinder. The throttling consists in having in one part of the cylinder a reduced charge of air carbureted at its most efficient exploding point.

I wish it distinctly understood that my internal combustion engine, herein illustrated and described, is in the form which I desire to construct it, and that any changes or variations may be made as may be convenient or desirable without departing from the salient features of my invention and I therefore intend the following claims to cover such modification as naturally fall within the lines of invention.

Having thus fully described my invention, what I claim as new and desire to secure by Letters Patent is:—

1. In an internal combustion engine, the combination of a cylinder and piston operating therein; two storage chambers, an air pump supplying air thereto, and an independent manually-operated means to inversely vary the capacity thereof, pipe connections between the cylinder and one of the storage chambers a carbureting means connected to each of the storage chambers.

2. In an internal combustion engine, a combustion chamber, two storage chambers one of which is connected to the combustion chamber, a carbureting means connected between the storage chambers, the said connection being the sole connection between the storage chambers, an air pump for supplying air to the storage chambers and manually-operated means, to inversely vary the capacity of aforesaid chambers, whereby the amount of perfect mixture flowing into the combustion chamber is regulated.

3. In an internal combustion engine, a means of regulation consisting in combination, a combustion chamber, two storage chambers connected together and to the combustion chamber, a carbureting means in the connection between the storage chambers, an air pump for supplying air thereto, and an independent manually-operated means to inversely vary the capacity thereof.

4. In a two-cycle engine, a combustion chamber, two storage chambers connected together by an equalizing pipe, a carbureting means connected in said equalizing pipe, an air pump for supplying air to the storage chamber, pipe connections between one storage chamber and the combustion chamber, means of regulating the volumes of the storage chambers, whereby the amount of a charge of carbureted air entering the combustion chamber is regulated.

5. In an internal combustion engine, a cylinder, a piston operating therein, mechanical inlet and exhaust valves, operated by the aforesaid piston, an ignition device in said cylinder, two storage chambers connected together by an equalizing pipe, a carbureting means connected in said equalizing pipe, pipe connections between the combustion chamber and one storage chamber, an air pump for supplying air to the storage chambers, an independent manually-operated means to inversely vary the capacities of the storage chambers whereby the amount of the charge of air, carbureted at its most efficient exploding point, admitted to the cylinder, is regulated.

This specification signed and witnessed this 27th day of March, A. D., 1907.
